UNITED STATES PATENT OFFICE.

WILLIAM F. LAUTENSCHLAGER, OF CINCINNATI, OHIO, ASSIGNOR TO LORENZ MUTHER, OF DENVER, COLORADO.

CEMENT-APPLYING MACHINE.

No. 913,829.

Specification of Letters Patent. Patented March 2, 1909.

Application filed January 27, 1908. Serial No. 412,840.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Cement-Applying Machines, of which the following is a specification.

My invention relates to cement applying machines, and is adapted, among other uses, for applying cement to leather or other fabrics, for instance, in the manufacture of shoes and similar articles.

In the present exemplification of my invention I shall describe the same as adapted for employment in applying a band of cement to the edges of vamps, or other parts of shoes, one of the objects of applying this band of cement being to hold the edge when turned over in the form of a bead, as is usual in shoe manufacture, and when so employed a viscous very slowly evaporating cement is used. The objections to applying this cement by hand with a brush are a waste of cement due to the stringing of the cement between the cement-pot and the work, and the application on the work of a wider band of cement than necessary, besides the danger from fire owing to the exposure of the cement, which is highly inflammable. In my improved device I avoid all these objections and apply a band of cement of the proper width without waste of cement and without exposure of the body of cement, while at the same time I retain the benefit accruing from the manner of the manual brush-application of the cement.

Objects of my invention are to apply the cement by machine with a motion imitating the motion employed in applying the cement with a brush by hand; to "brush" the cement upon the stock by means of a rotary cement-feeding brush whose peripheral movement is differentiated from the feed of said stock; to provide a feeding device for the stock and a rotary cement-applying brush, with means for causing the stock-contacting portion of the periphery of the brush to travel in the direction of the feed faster than said feed; and to provide improved cement and stock-feeding means; and the invention will be readily understood from the following description and claims, and from the drawings, in which latter:

Figure 1 is a front elevation of my improved device. Fig. 2 is an end elevation of

the same with the cement-cup partly broken away. Fig. 3 is a vertical section of the feeding end of my improved device taken on the line $z-z$ of Fig. 2. Fig. 4 is a plan view of the feeding end of my improved device partly in section on the line $y-y$ of Fig. 5. Fig. 5 is an end elevation of the same. Fig. 6 is a vertical section taken on the line $x-x$ of Fig. 1 showing the brushing effect of the brush in the cement-application and showing the brush in end elevation with the feed-wheel removed. Fig. 7 is a vertical section of the cement-feeding parts taken on the line $z-z$ of Fig. 2 and showing the transverse brushing effect of the brush; and, Fig. 8 is an enlarged end elevation of the feed-wheel and adjacent parts.

1 represents the base from which a preferably goose-neck column 2 extends and which supports a cement-cup 3 which may have a cover 4.

5 is a table suitably secured to the base. A drive-shaft 6 is journaled in a bearing 7 in the column and has suitable drive means thereon, as a pulley 8.

9 is an arm depending from the column on which there is a bearing 10 for the drive-shaft. This arm also has a bearing 11 for an intermediate shaft 12 supporting gears 13 14, the gear 13 meshing with a gear 15 on the drive-shaft.

16 is a sleeve journaled loosely about the drive-shaft and carries a gear 17 which meshes with the gear 14.

18 is a cement-applying brush, the bristles of which are mounted in a housing 19 secured to the sleeve 16, as by a screw 20, causing the brush and sleeve to rotate together.

21 is a feed-wheel for the stock, shown at a , the feed-wheel being secured to the shaft 6, as by being mounted on a reduced shank 22 of the shaft, a screw 23 clamping the feed-wheel between the screw and the shoulder 24 on the shaft. The sleeve 16 rotates about the shaft 6, and for lubricating the same, the screw 23 is provided with a longitudinal bore 25 which communicates with lateral discharge-openings 27 extending to the journal on the shaft 6 for the sleeve.

It will be noted from Fig. 8 that the diameter of the applying brush 18 is slightly greater than the diameter of the feed-wheel for purposes hereinafter described. The sizes of the gears 13, 14, 15 and 17 are so

105

110

related as to drive the applying-brush at a different speed from the speed of the feed-wheel and preferably rotating the brush in the same direction as the feed-wheel, that is, causing their stock-contacting faces to move in the direction of feed of the stock, also for purposes hereinafter described.

31 is a head in which a cement-feeding roller 32 rotates, the roller being secured to a shaft 33 by a screw 34. The shaft 33 is journaled in bearings 35 36, the bearing 36 being shown removable as by means of screws 37. A gear 38 is mounted on the shaft 33 and meshes with the gear 14. The head is supported from the column and has cement-feeding connection with the cement-cup. I have shown this accomplished by providing the cup with a shank 41 secured in a bearing 42 on the column, the head being screwed upon the shank by means of the threaded connection 43 which clamps the bearing between the cup and head. The shank 41 has a bore 44 communicating with a bore 45 in the head, in which latter there is a valve 46 for regulating the supply of cement to the cement-applying roller. The applying-face 47 of the cement-applying roller is provided with recesses 48 for receiving the cement, and the head is provided with lips 49 50 which act as wipers for the applying-face 47 for preventing waste of cement between the lips and applying-face, the cement being fed in the recesses to the rotary cement-brush, the brush in turn wiping the cement out of the recesses and applying it to the stock. The lip 50 is provided with a wiping edge 51 receding toward the middle of the roller, the operation being to direct any cement there may be on the applying-face 47 after the same has passed the applying-brush toward the middle of the applying-face for causing this cement to be received by the recesses, and again fed through the applying-head, at the same time preventing particles of leather or dirt from clogging the applying-roll.

It will be noted that the bore 45 has a mouth 52 extending toward the feeding portion or front of the periphery of the roller and that this mouth is backed by a roof 53 which gradually approaches the roller, the mouth spanning a plurality of the recesses 48, the object being to cause the weight of the cement to bear upon the roller at a plurality of said recesses, the roller in turning carrying the cement with it and the roof forming a wedge for pressing the cement into the recesses of the roller for causing proper filling of the latter and feeding of the cement, and preventing a rolling motion of the cement above the roller, it being understood that cement employed for the particular purpose mentioned is liable not to flow freely.

55 is a stock-support which preferably

extends above the plane of the table and whose stock-supporting-face 56 is preferably arranged on a curve from front to rear for readily permitting passage of the goods there-over and reducing the extent of contact between the feed-wheel and applying-brush and the stock. This stock-support is shown mounted on a lever 57 pivoted on a pin 58 in bearings 59 on the lower face of the table. The lever has a heel 61 against which a spring 62 presses, the spring being received in a bore 63 of an adjusting screw 64 adjustable in a threaded bearing 65 of a lug 66 depending from the table, the inner end of the spring being received in a depression 67 of the heel for preventing displacement of the spring, the function of the spring being to urge the stock-support upwardly toward the feed-wheel and brush and permit the stock-support to yield when stock is fed between the feed-wheel and the support. To adjustably limit the upward movement of the stock-support I provide an adjustable set-screw 68 threaded in the lever and adapted to strike a lug 69 on the lower face of the table. On the stock-support there is a stock-gage 70 which I prefer shall be integral with the stock-gage for preventing catching of the bristles of the brush between the stock-support and gage. The stock-support operates through an opening 71 in the table.

In operation, the stock is placed in position on the stock-support for having contact made therewith by the feed-wheel, which thereupon takes hold of the stock for feeding the same through the machine. The feeding periphery of the roller is preferably provided with cross-ribs 72 and the roller is preferably narrow, the stock-gage 70 being also preferably short for permitting curved edges of stock to be fed through the machine against the gage. Stock of this kind is usually skived, that is, it is cut so that its thickness tapers to a thin edge for permitting the edge to be readily turned backwardly upon itself to form a bead. As heretofore stated the brush is of larger diameter than the diameter of the feed-wheel. The thin skived edge of the stock is received against the gage, the brush being between the gage and the feed-wheel for permitting the feed-wheel to act upon a thicker portion of the stock. The brush being of greater diameter than the feed-wheel, it applies the cement throughout the width of the skived portion irrespective of differences in thickness across the same, as the bristles of the brush give to sufficient extent to contact the stock with the entire width of the brush, as more fully illustrated in Fig. 7. The brush being of larger diameter than the feed-wheel, causes the bristles in their contact with the stock to bend and to be received within the recesses of the cement-feeding roller. In order that the brush may

have a brushing effect upon the stock similar to the brushing effect in the hand-application of the cement-brush, I differentiate the movement of the cement-applying brush from the stock-feed, and I prefer to accomplish this by rotating the applying brush at a greater speed than the feeding speed applied to the stock. I cause a bending of the bristles of the brush from their normal radial positions toward the feeding-in side of the brush and cause these bent bristles to spring rearwardly as soon as they have turned beyond their vertical positions at the lower side of the brush. In the form shown I obtain the differential movement at the peripheries of the feed-wheel and cement-applying brush while rotating them in the same direction and by rotating the brush at greater speed than the feed-wheel. I have found an advisable differential in rotation to be one and a half to one, but this ratio may be departed from or increased or diminished as may be desired without departing from the spirit of my invention. I have indicated the direction of rotation of the brush in the present exemplification of my invention by the arrow *b*, the direction of travel of the stock by the arrow *c*, and the direction of rotation of the cement-roller by the arrow *d*.

30 In order to protect the stock from the gears adjacent the cement-applying brush and prevent the stock being drawn into the gears I provide the guard 73, which is secured to the arm 9 by screws 74 and extends around the 35 bottom and to front and rear of the gears adjacent the brush. The work-support is provided with an outside slope 75 for readily directing the stock to the top of the support.

Having thus fully described my invention 40 what I claim as new and desire to secure by Letters Patent is:

1. A cement applying machine comprising a rotary cement-applying brush and stock-feeding mechanism and means for rotating 45 said brush at greater speed than the speed of feed of said feeding mechanism.

2. In a cement applying machine, the combination of a rotary cement-applying brush, means for rotating the same, a stock-support, 50 a feeding device for the stock, means for operating said stock-feeding device, means for yieldably urging approach between said stock-support and said cement-applying brush, said means for rotating said cement- 55 applying brush and means for operating said stock-feeding device embracing means for rotating the periphery of said cement-applying brush at greater speed than the speed of feed of said stock-feeding device.

60 3. In a cement applying machine, the combination of a stock feed-wheel and a cement-applying brush, having common rotary axes and means for rotating said brush faster than said feed-wheel, said brush being of greater 65 diameter than said feed-wheel.

4. In a cement applying machine, the combination of a stock feed-wheel and a cement-applying brush having common rotary axes, and means for rotating said brush and feed-wheel with differentiated movement. 70

5. In a cement applying machine, the combination of a stock feed-wheel, a rotary cement - applying brush, a cement - applying roller having cement-receiving recesses into which said brush is received for wiping said cement from said recesses, said brush being of greater diameter than said feed-wheel. 75

6. In a cement applying machine, the combination of a stock feed-wheel, a rotary cement - applying brush, a cement - applying 80 roller having cement-receiving recesses into which said brush is received for wiping said cement from said recesses, said brush being of greater diameter than said feed-wheel, and means for rotating said brush and feed-wheel 85 in the same direction and with greater speed in said brush than said feed-wheel.

7. In a cement applying machine, the combination of a stock feeding-means, a cement-applying brush, a stock-support, and a stock 90 gage, said brush operating opposite said stock - support between said stock feeding-means and stock-gage, substantially as described.

8. In a cement applying machine, the combination of a stock feeding-means, a cement-applying brush, a stock-support, and a stock-gage, said stock feeding-means and stock-support having movement between each other for accommodating the stock, and said 100 cement-applying brush operating between said stock feeding-means and stock-gage, substantially as described.

9. In a cement applying machine, the combination of a stock feeding-means, a cement-applying brush, a yieldable stock-support, 105 and a stock-gage mounted on and yielding with the latter, said cement-applying brush operating between said stock-feeding-means and said stock - gage, substantially as described. 110

10. In a cement applying machine, the combination of a feed-wheel and a cement-applying brush having common rotary axes, means for rotating said cement-applying 115 brush and said feed-wheel, a yieldable stock-support having a stock-gage thereon and movable therewith, said brush operating between said feed-wheel and said stock-gage, substantially as described. 120

11. In a cement applying machine, the combination of a feed-wheel, a shaft for rotating the same, a cement-applying brush, a sleeve rotatable about said shaft on which said brush is mounted, an intermediate shaft, 125 and gearing between said intermediate shaft and said first-named shaft and sleeve, substantially as described.

12. A cement applying machine comprising the combination of a rotary cement-ap- 130

plying brush, feeding means, a stock-support and a rotary cement-feeding roller having cement-carrying recesses, the bristles of said brush received within said recesses for wiping the cement therefrom and transferring said cement to the stock with a bending motion of the bristles, substantially for the purpose specified.

13. In a cement applying machine, the combination of a stock feeding-means, a table, a stock-support, projecting above the plane of extension of said table and having an upper surface curved upwardly in the direction of feed of said feeding means and provided with a lateral slope toward said table, and a cement - applying brush operating above said stock-support, substantially as described..

14. A cement applying machine comprising a cement-head and a cement-feeding roller rotatable therein and provided with cement-carrying recesses, said head having wiping lips for said cement, one of said lips toward which said cement-recesses move from outside said head being indented toward the central line of said recesses for causing the cement on said roller to be wiped thereby into said recesses, substantially as described.

In testimony whereof, I have subscribed my name hereto in the presence of two subscribing witnesses.
